(57) **CLAIM**

The ornamental design for a tire sidewall, as shown and described.

DESCRIPTION

FIG. 1 is a perspective view of a tire sidewall showing my new design;

FIG. 2 is a front view thereof;

FIG. 3 is a top view thereof, a bottom view being a mirror image of FIG. 3;

FIG. 4 is a right side view thereof, a left side view being a mirror image of FIG. 4;

FIG. 5 is a rear view thereof;

FIG. 6 is a fragmentary enlarged front view showing the details of the sidewall defined by a dash-dot broken line 6 in FIG. 2;

FIG. 7 is a fragmentary enlarged front view showing the details of the sidewall defined by a dash-dot broken line 7 in FIG. 6; and,

(Continued)

FIG. 8 is a cross-section view taken along line 8-8 in FIG. 7.

The dash-dash broken lines illustrate portions of the tire that form no part of the claimed design.

1 Claim, 8 Drawing Sheets
